UNITED STATES PATENT OFFICE.

PATRICK McDONALD, OF WESTVILLE, ILLINOIS.

ACETYLENE GAS GENERATOR.

Application filed February 14, 1927. Serial No. 168,119.

This invention relates to improvements in acetylene gas generators and has for its primary object the provision of means for maintaining an unobstructed valve controlled water outlet into the carbide chamber of the generator, so as to maintain the generator at a high state of efficiency until the carbide has become exhausted.

In acetylene generators of the type commonly used for miners' lamps, the efficiency of the lamp is materially reduced when approximately one-half of the supply of carbide has been used. This is due to the failure of the water to pass through the dead or used carbide. When this occurs, the miner will refill the carbide chamber with the result that approximately one-half of the carbide is wasted.

To overcome this and other disadvantages, the present invention provides means for removing or scraping away the "dead" carbide which has collected around the water outlet, so that the water may reach fresh carbide and the efficiency of the lamp maintained without undue waste.

With the above and other objects in view, the invention further includes the following novel features and details of construction, to be hereinafter more fully described, illustrated in the accompanying drawings and pointed out in the appended claim.

In the drawings:—

Figure 1 is a sectional view of an acetylene lamp of the type commonly used by miners, with the invention applied.

Figure 2 is a detail perspective view of the scraper.

Referring to the drawings in detail wherein like characters of reference denote corresponding parts, the invention is shown in connection with a miner's lamp, although it is adapted for use in connection with acetylene gas generators of various types.

The reference character 10 indicates a carbide chamber and 11 a water reservoir, the reservoir and chamber being attachably connected as indicated at 12, whereby the bottom wall of the water reservoir forms a closure for the carbide chamber so that the latter may be properly charged. Water is introduced into the reservoir 11 which is closed by a plug 13, while a tubular member 14 extends from the water reservoir into the carbide chamber and provides a conduit by means of which water is fed to the carbide within the chamber 10. An opening

15 is provided for the passage of water from the reservoir 11 into the conduit. A pipe 16 extends from the water reservoir and has its inner end in communication with the upper portion of the carbide chamber so that gas may pass through this pipe to a suitable burner (not shown), the latter being mounted within a reflector 17. The outlet end of the conduit is controlled by a valve 18 which is adapted to seat against the lower end of the tubular member 14. This valve is carried upon a stem 19 which has a loose threaded engagement with the inner end of the tubular member 14 as indicated at 20. The stem 19 extends upward through the top of the lamp and is provided with an operating handle 21. By means of the handle 21 the valve may be rotated to move the stem toward and away from the end of the tubular member 14 so as to control the passage of water from the conduit into the carbide chamber. All of the foregoing may be of the usual or any other suitable construction.

As before stated, operation of the generator will result in a collection of "dead" carbide around the outlet end of the conduit, and as water will not penetrate this dead carbide, the efficiency of the lamp is reduced. To obviate this disadvantage, there is secured to the valve 18 a skeleton sleeve 22 which is shown in detail in Figure 2 of the drawings.

This sleeve has a free working fit upon the outside of the tubular member 14 so that when the valve 18 is rotated, rotation will be imparted to the sleeve. Extending longitudinally upon diametrically opposite sides of the sleeve are scraper ribs 23 and when the valve 18 is rotated to open and close the outlet end of the conduit, these ribs 95 will act to scrape away the dead carbide and will maintain an unobstructed outlet at the lower end of the conduit when the valve is in open position. Due to the loose threaded engagement between the valve stem and the

tubular member, water will pass in sufficient quantities to the outlet when the valve is open. Operation of the valve will thus maintain the generator at its proper efficiency until all of the carbide within the 105 chamber 10 has become exhausted.

The invention is susceptible of various changes in its form, proportions and minor details of construction and the right is herein reserved to make such changes as properly fall within the scope of the appended claim.

Having described the invention what is claimed is:—

In an acetylene gas generator, a casing including a carbide chamber, a water reservoir, a conduit opening into the carbide chamber for directing water from the reservoir into said chamber, a valve for controlling the passage of water into said chamber, a sleeve rotatable about the conduit and secured to the valve whereby operation of

the latter will rotate the sleeve, said sleeve having elongated openings therein and radially disposed scraper blades carried by and extending longitudinally along opposite sides of the sleeve between the openings and operable to maintain an unobstructed outlet for the water when the valve is in open position.

In testimony whereof I affix my signature.

PATRICK McDONALD.
